UNITED STATES PATENT OFFICE

113,393

DESIGN FOR A TEXTILE FABRIC

Julia Morris, New York, N. Y.

Application January 5, 1939, Serial No. 82,170

Term of patent 3½ years

To all whom it may concern:

Be it known that I, Julia Morris, a citizen of the United States of America, residing in New York city, in the Borough of Manhattan, county and State of New York, have invented a new, original, and ornamental Design for a Textile Fabric, of which the following is a specification, reference being had to the accompany drawing, forming part thereof, wherein the figure is a plan view of a piece of textile fabric showing my new design.

The design, as a unit, comprises two identical rows of figures, facing in opposite directions, and separated by a multi-colored band. The design repeats itself along the width of the fabric, and in alternate succession throughout the length of the fabric.

I claim:

The ornamental design for a textile fabric, substantially as shown and described.

JULIA MORRIS.
